SIGNALING SYSTEM.

Application filed August 19, 1924. Serial No. 732,800.

This invention relates to signaling systems, more particularly those adapted for submarine signaling and its object is to protect such a system from excessive current impulses occurring during switching operations.

In my copending application, Serial No. 690,709, filed February 5, 1924, there is described in detail a submarine signaling system in which the received signaling current waves are shaped and amplified before passing into the receiving apparatus. In such a system, if used for alternate sending and receiving, it is necessary to provide some

means for protecting the receiving apparatus from the flow of excessive currents occurring when the cable is disconnected from the sending apparatus and connected to the receiving apparatus. At the end of the sending period after the transmitter has been disconnected from the cable and connected to earth there flows from the cable a current which is due to the combined action of the earth current flowing in the cable caused by

different potentials of the earth at the respective terminals and the flow to earth of the electric charge absorbed by the cable dielectric during the sending period. This absorbed charge may take several minutes to completely drain off and there still remain the earth currents which are usually capable of producing a potential between cable and earth far in excess of the normal voltage of the signal for which the system is designed.

If the input circuit of the amplifier is connected between the cable and earth and the direct connection between the cable and earth removed there will result a current pulse of many times the voltage of the normal signaling current and containing abnormally high frequency components. Since the amplifier and its input circuit are designed so that up to a certain frequency, amplification increases in proportion to frequency, the

amplifier impulses upon reaching the receiving mechanism may be of sufficient amplitude to seriously damage the apparatus. Furthermore, the high voltages impressed upon the input circuits of the latter stages of the amplifier will override the C batteries associated with the grids and, by allowing a current to flow between the grids and filaments, will seriously disturb the normal

charges of the coupling condensers. The amplifier will thus be rendered inoperative for several minutes or until the normal grid voltages are again established by the charge or discharge of several large condensers through high resistances.

In accordance with a feature of the present invention, the various switching operations are caused to take place in a certain sequence so that the amplifier and receiving apparatus associated therewith are protected from excessive current impulses.

This and other features of the invention will be more clearly understood by reference to the accompanying drawings in which there is disclosed a signaling system employing the features of the invention.

Referring to the drawing, there is provided a shaping amplifier A of the type described in detail in my copending application mentioned above, combined with a shaping network N of the type described in my copending application Serial No. 734,581, filed August 28, 1924. In transmitting current impulses over a long cable, low frequencies are attenuated much less than the high frequencies and the low frequencies are also retarded in phase more than the higher frequencies. The network N is designed to correct, in part at least, the received impulses for phase shift and for attenuation. At the same time, the arrangement disclosed provides a high impedance termination for the cable for all signal frequencies as described in detail in a copending application of John J. Gilbert, Serial No. 734,580, filed August 28, 1924.

The input circuit of the first amplifier tube 5 is connected to the secondary winding of transformer 6 which is included in the first shaping network N. Between the output circuit of amplifier tube 5 and the input circuit of amplifier tube 7 there is provided a shaping network so designed as to further compensate for the attenuation of the signaling impulses. Between the output circuit of amplifier tube 7 and the input circuit of amplifier tube 8 there is a second network which is designed to reduce high frequency interference. A similar network but having slightly different constants in order to be effective at slightly different frequencies, is connected between the output

circuit of amplifier tube 8 and the input circuit of amplifier tubes 9 and 10 which have their elements connected in parallel to provide a larger output. Coupling condensers 5 11-11 and shunt condensers 12-12 are provided between stages as shown.

The change from sending to receiving positions and vice versa, is accomplished by means of switch S comprising a handle 15 by 10 means of which the brush 16 successively connects segment 17 with segments 18, 19 and 20, while brush 21 connects segment 22 with segments 23 and 24. The conductor of cable C is connected to segment 17 while the 15 grounded transmitter T is connected to segment 18 and one terminal of the shaping network is connected to segment 20. Segment 19 is grounded and the sea ground 20 of the cable C is connected as shown to the shaping network. Segment 22 is connected to the common point of batteries 26 and 27, the other terminals of which are connected through relay windings 28 and 29 respectively, to segments 24 and 25. The relay armature 30, when in engagement with the contact 31 is adapted to place a short-circuit across the primary winding and added primary resistance of the auto-transformer 32 positioned between the first 30 and second stages of the amplifier. The receiving mechanism R, which in general, will consist of a siphon recorder, is connected in the output circuit of the last stage of the amplifier.

35 With the brush arm in the position shown, the circuit is arranged for sending current impulses from the transmitter T over the conductor of cable C. The shaping network is disconnected from the line at segment 20 and the armature 30 is in engagement with contact 31 thus placing a short-circuit across the amplifier. If the handle 15 is operated in a clockwise direction, the brush 16 passes from segment 18 onto segment 19 thus disconnecting the transmitter T from segment 17 which is connected to the cable conductor and connecting the cable to ground through segment 19. Upon further rotation, the cable continues grounded until brush 16 passes from segment 19 to segment 20 thus connecting the cable with the input circuit of the shaping network. Brush 21 wipes over segment 23 causing an impulse to flow from battery 27 through the winding 29 of the 50 relay but no change takes place in this relay since the impulse is in the direction to maintain the armature in engagement with contact 31. In the last stage of the switching operation, brush 21 passes from segment 23 to segment 24 and an impulse is then sent through relay winding 28 causing the armature 30 to be operated in the opposite direction thereby breaking contact with 31 and opening the short-circuit across the inter-stage transformer 32. The system is now in

position for receiving and no further change takes place until it is desired to switch from the receiving to the sending position.

When it is desired to switch to the sending position the handle 15 is slowly operated in 70 an anti-clockwise direction. As the brush 21 engages segment 23 a circuit is closed from battery 27 to winding 29, segment 23, brush 21 and segment 22 back to the battery thus energizing the armature 30 and causing 75 it to engage with contact 31 and place a short circuit across the interstage transformer 32. As rotation continues, brush 16 passes from segment 20 to segment 19 thus disconnecting the network from the cable 80 conductor which is now connected to earth. The cable conductor remains connected to earth until brush 16 passes from segment 19 to segment 18 thus removing the earth connection and connecting transmitter T to the 85 cable conductor. The switching mechanism S is so designed that a period of approximately ten seconds may be caused to elapse during changing from one position to another thus providing time for the draining 90 of the greater portion of the charge absorbed by the cable C. The relay which controls the short circuiting of the amplifier is so arranged that the armature remains in whatever position it was last energized. This 95 may be accomplished by employing separate windings as shown or by the use of a polarized relay.

For the most satisfactory operation, it is necessary that the short circuit be applied 100 between the first and second stages of the amplifier. If a short circuit should be applied across the secondary coil of the input transformer 6 and maintained until after the shock caused by applying the residue 105 cable voltage to the shaping network has disappeared, the initial shock to the amplifier would be avoided; but as there are always currents of very low frequency flowing in the cable network and the removal or application of the short circuit to the transformer secondary changes the network constants and the earth current abruptly, an impulse or 110 oscillation is still produced which is strong enough to cause trouble. When the short 115 circuit is applied to the primary side of the interstage auto-transformer as shown in the drawing, the pulse produced on connecting the cable to the amplifier produces a merely transient effect on the first stage of the amplifier which contains no grid coupling condenser and as the output of the first stage is short circuited the pulse does not pass through the amplifier. When this short circuit is removed, after the strong impulse has 120 died down, a weak impulse may still be produced, due to the application of the current leaking through the first interstage coupling condenser to the auto-transformer primary winding and also due to any low frequency 125 130

earth currents or interference of higher frequencies which may be present and impress a voltage between the first stage of the vacuum tube plate and its filament. This pulse 5 however is usually of the same order as the normal signal and does not cause any damage. If the short circuit is connected between the second and third or between the third and fourth stages of the amplifier, the 10 current impulses occurring at the time the short circuit is removed are of sufficient strength when amplified to override the C batteries and render the apparatus inoperative until the normal grid voltages are again 15 established. While in the arrangement shown a rotatable switch is disclosed in order to more clearly indicate the sequence of the steps in switching from sending to receiving positions or vice versa, it will be 20 understood that in operation, these switching operations may be performed automatically and in their correct sequence by means of relays.

What is claimed is:

- 25 1. In a signaling system comprising a cable, a sending mechanism and a receiving mechanism having an amplifier associated therewith, means for preventing excessive current impulses at the time of completing 30 the circuit between the receiving mechanism and the cable.
2. In a signaling system comprising a cable, a sending mechanism and a receiving mechanism having an amplifier associated 35 therewith, means for bridging a low impedance circuit across the amplifier to prevent excessive current impulses at the time of connecting the receiving apparatus to the cable.
- 40 3. In a signaling system comprising a cable, a sending mechanism and a receiving mechanism having an amplifier associated therewith, an electromagnetic device operable during the time of connecting the amplifier and receiving mechanism to the line 45 for short-circuiting the amplifier.
4. In a signaling system comprising a cable, a sending mechanism, a receiving mechanism having an amplifier associated therewith and a switching mechanism for alternately connecting the sending mechanism and the receiving mechanism with its associated amplifier to the cable, an electromagnetic device under the control of said switching mechanism for protecting the amplifier and receiving mechanism from excessive current impulses occurring during the operation 55 of the switching mechanism.
5. In a signaling system comprising a 60 cable, a sending mechanism, a receiving mechanism having an amplifier associated therewith and a switching mechanism for alternately connecting the sending mechanism and the receiving mechanism with its 65 associated amplifier to the cable, an electro-

magnetic device under the control of said switching mechanism for connecting a bridging circuit across the amplifier to prevent the flow of excessive current impulses therethrough during the switching operations. 70

6. In a signaling system comprising a cable, a sending mechanism, a receiving mechanism having an amplifier associated therewith and a switching mechanism for alternately connecting the sending mechanism and the receiving mechanism with its associated amplifier to the cable, an electromagnetic device for placing a short circuit bridge across the amplifier at the instant of connecting the amplifier to the cable. 80

7. In a signaling system, comprising a cable, a sending mechanism, a receiving mechanism having an amplifier associated therewith and a switching mechanism for alternately connecting the sending mechanism and the receiving mechanism with its associated amplifier to the cable, an electromagnetic device automatically controlled by the switching mechanism to short circuit the amplifier at the instant the cable is connected thereto. 90

8. In a signaling system, a cable, a sending mechanism, a receiving mechanism having an amplifier associated therewith, a switching mechanism for alternately connecting the sending and receiving mechanisms to the cable, and means under the control of the switching mechanism for rendering the amplifier inoperative at the instant the cable is connected thereto. 95

9. In a signaling system, a cable, a sending mechanism, a receiving mechanism having an amplifier associated therewith, a switching mechanism operable at the end of the sending period for disconnecting the cable from the transmitting mechanism and connecting it to earth for a short interval before connecting it to the receiving mechanism, and means under the control of the switching mechanism for rendering the amplifier inoperative until after the cable is connected thereto. 100

10. In a signaling system, a cable, a sending mechanism, a receiving mechanism having an amplifier associated therewith, a switching mechanism operable at the end of the sending period for disconnecting the cable from the transmitting mechanism and connecting it to earth for a short interval before connecting it to the receiving mechanism, and means automatically operated by the switching mechanism for short circuiting the amplifier until after the cable is connected thereto. 105

11. In a signaling system comprising a 125 cable, a sending mechanism, a receiving mechanism, a multi-stage amplifier associated with said receiving mechanism, and means for connecting a short-circuit across said amplifier to prevent excessive current 130

impulses at the time of connecting the receiving mechanism to the cable.

12. In a signaling system comprising a cable, a sending mechanism, a receiving mechanism, a multi-stage amplifier associated with said receiving mechanism, and means for connecting a short circuit across

the output circuit of the first stage of said amplifier.

In witness whereof, I hereunto subscribe my name this 15th day of August A. D., 1924.

AUSTEN M. CURTIS.
